CHILD'S BIB

Sunny Asch, New York, N. Y.

Application November 9, 1939, Serial No. 303,502

5 Claims. (Cl. 2-49)

This invention relates to new and useful improvements in a child's bib.

The invention has for an object the construction of a bib which is characterized by a front sheet of moisture absorbent cloth material adapted to engage over the chest and front of a baby and having a neck cutout, a collar-like extension mounted upon the said front sheet in a particular manner, and an arrangement for supporting the bib in place upon the child.

Still further the invention contemplates the use of a waterproof back sheet for extending behind the front sheet and preventing the clothes of the child from becoming wet by moisture which may pass through the moisture absorbent sheet.

Still further the invention contemplates the provision of novel means for releasably connecting the waterproof back sheet in position upon the back of the front moisture absorbent sheet.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a child's bib constructed according to this invention.

Fig. 2 is a horizontal sectional view taken on the line 2-2 of Fig. 1.

Fig. 3 is a fragmentary vertical sectional view taken on the line 3-3 of Fig. 1.

Fig. 4 is a horizontal sectional view taken on the line 4-4 of Fig. 1.

Fig. 5 is a fragmentary front elevational view of a child's bib constructed in accordance with a modification of this invention.

Fig. 6 is a fragmentary front elevational view of a portion of the back sheet illustrated in Fig. 5.

Fig. 7 is a fragmentary front elevational view of a portion of the front sheet illustrated in Fig. 5, with the back sheet removed.

Fig. 8 is a fragmentary vertical sectional view taken on the line 8-8 of Fig. 5.

Fig. 9 is a perspective view of the absorbent cloth bib member.

The child's bib, in accordance with this invention, includes a front sheet of moisture absorbent cloth material 10 adapted to engage over the chest and front of a child and having a neck cutout 11. A collar-like extension 12 is mounted upon the said front sheet 10 for location beneath the chin of the child and projects frontwards. A

strip of tape 13 is attached to the ends of the neck opening by which the bib may be tied in place on the child. A waterproof back sheet 14 is provided for extending behind the front sheet 10 to prevent the passage of liquids through the front sheet which may wet the baby's clothes.

Preferably, the front sheet 10 is made of towelling material. A strip of binding material 15 is extended around the edges of the sheet 10 for finishing same. The top area 15a of this binding material serves to hold the top edge of the sheet 10 relatively stiff so that it stands extended even though it is supported at points inwards from the side edges by the tape 13.

The collar-like extension 12 is also formed from towelling material. A strip of the material is bent at its longitudinal center 12a so as to be of double layers. The outer ends of these double layers are stitched together and the side edges engage immediately behind an inturned flange 10a bent inwards from the neck opening 11 of the material 10. The tape 13 extends around the back of the neck opening 11 and also has a flange portion 13a bent inwards from an edge thereof and located adjacent the side edges of the layers of the collar-like extension 12. A line of stitches 16 is engaged through the flanges 10a and 13a and through the edge portions of the layers of the collar-like extension 12 which are disposed between the said flanges. The collar-like extension 12 is fashioned to project outwards, as clearly illustrated in Figs. 1 and 3. The purpose of this arrangement is to have the extension extend underneath the baby's chin and so catch any drip of food while the baby is being fed. The other edge of the tape 13 is held down by a line of stitches 17.

The back sheet 14 is also formed with a neck cutout corresponding with the neck cutout 11. A strip of binding material 18 is engaged upon the neck cutout of the sheet 14. The outer edges of the sheet 14 are finished with ornamental serrated edge portions 19. A means is provided for releasably connecting the front sheet 10 with the back sheet 14 in a way so that the back sheet 14 is supported in position. This means includes a pair of loops 20 secured to the sides of the neck opening of the sheet 14. The ends of the tape 13 pass through these loops 20 and thus the back sheet is supported. The tape 13 may be engaged around the back of the child's neck to secure the bib in position.

In Figs. 5 to 8 inclusive, a modified form of the invention has been disclosed which distinguishes from the prior form in the construction

of the means for releasably connecting the front and back sheets together. In accordance with this invention the back sheet 14' has the two sections of its top edge adapted to be bent frontwards along the line AB, schematically illustrated in Fig. 6. At this bent area each top section of the back sheet is formed with a button-hole opening 22. The ends of the tape 13 engage through these buttonhole openings 22 for supporting the back sheet. Snap fasteners 23 are mounted upon the adjacent faces of the forward bent top edge sections and the material beneath these sections and are cooperative through buttonhole openings 24 formed in the material of the front sheet 10. In other respects this form of the invention is similar to the previous form and like parts may be identified by corresponding reference numerals.

In Fig. 5 the means for releasably connecting the front and back sheets 10 and 14 respectively together has been illustrated in its operative position. To disconnect the sheets it is first necessary that the front sections of the top portions of the back sheet be pulled forwards to open up the snap fasteners 23. Then the front and back sheets may be removed relative to each other to disengage the tape ends 13 from the openings 22. The parts may be reassembled by following the disengaging steps in reverse order.

It is to be understood that this rib may be of any desired material such as toweling, knit cloth, absorbent paper, etc., also that it may be made of any desired shape and ornamentation.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A child's bib, comprising a front sheet of moisture absorbent cloth material adapted to engage over the chest and front of a child and having a neck cutout, a collar-like extension mounted on said front sheet beneath the chin of said child and projecting frontwards, a strip of tape attached to the ends of the neck opening by which the bib may be tied in place on the child, a waterproof back sheet for extending behind said front sheet, and means for releasably connecting said sheets together, comprising loops mounted upon said back sheet and said strip of tape having its end portions engaged through said loops.

2. A child's bib, comprising a front sheet of moisture absorbent cloth material adapted to engage over the chest and front of a child and having a neck cutout, a collar-like extension mounted on said front sheet beneath the chin of said child and projecting frontwards, a strip of tape attached to the ends of the neck opening by which the bib may be tied in place on the child, a waterproof back sheet for extending behind said front sheet, and means for releasably connecting said sheets together, said back sheet

having sections of its top edge engaged over the top edge of said front sheet, snap fasteners mounted upon said back sheet and acting between openings in the front sheet for releasably holding said bent downsections, and said strip of tape having its ends passing through openings formed in the bent areas of said down-turned top edges.

3. A child's bib, comprising a front sheet of moisture absorbent cloth material formed with a neck cutout having its edge bent rearwards, a strip of tape having a U-shaped cross-section and having its layers disposed on and secured to the front and rear faces of the edge portion of said sheet of material except at said neck cutout, said tape having both its layers disposed behind said sheet of material at said neck cutout and its rearmost layer attached to the back face of said sheet of material beneath said rearwardly bent edge, a strip of moisture absorbent cloth material doubled upon itself and having the free ends of its layers disposed between the adjacent faces of said rearwardly bent edge and said tape and the junction of its arms projected forwards forming a collar.

4. A child's bib, comprising a front sheet of moisture absorbent cloth material formed with a neck cutout having its edge bent rearwards, a strip of tape having a U-shaped cross-section and having its layers disposed on and secured to the front and rear faces of the edge portion of said sheet of material except at said neck cutout, said tape having both its layers disposed behind said sheet of material at said neck cutout and its rearmost layer attached to the back face of said sheet of material beneath said rearwardly bent edge, a strip of moisture absorbent cloth material doubled upon itself and having the free ends of its layers disposed between the adjacent faces of said rearwardly bent edge and said tape and the junction of its arms projected forwards forming a collar, and means for securing together the edge of said neck cutout, the free ends of the layers of said strip of material and the layers of said tape as a unit.

5. A child's bib, comprising a front sheet of moisture absorbent cloth material formed with a neck cutout having its edge bent rearwards, a strip of tape having a U-shaped cross-section and having its layers disposed on and secured to the front and rear faces of the edge portion of said sheet of material except at said neck cutout, said tape having both its layers disposed behind said sheet of material at said neck cutout and its rearmost layer attached to the back face of said sheet of material beneath said rearwardly bent edge, a strip of moisture absorbent cloth material doubled upon itself and having the free ends of its layers disposed between the adjacent faces of said rearwardly bent edge and said tape and the junction of its arms projected forwards forming a collar, and means for securing together the edge of said neck cutout, the free ends of the layers of said strip of material and the layers of said tape as a unit, comprising a line of stitches engaged through these parts.
